PADDED SPRING CUSHION UNIT

Abraham Krakauer, Brooklyn, N. Y., assignor to
 Kay Manufacturing Corporation, Brooklyn,
 N. Y., a corporation of New York

Application October 23, 1940, Serial No. 362,341

3 Claims. (Cl. 5—351)

This invention relates to inner spring cushions and particularly to the padding therefor.

Inner spring units have customarily been enclosed in burlap or the like casings and shipped in that condition, or without burlap or other covers, to the upholsterer or furniture manufacturer. To additionally pad the cushion, separate pads of sisal or the like have also been supplied for arrangement by the upholsterer around the unit. To complete the cushion, the upholsterer arranges a sisal pad on each face of the unit, and if desired also on its side and end edges, which pad is then covered with a layer of cotton or the like batting, the whole being finally enclosed in the outer wearing cover of the cushion.

The separate handling and shipment of the sisal pads and spring units and their later assembly into the cushion has appeared heretofore to be unavoidable. It is expensive and wasteful, however, owing to loss of sisal from the pads and its adhesion to fabric and other parts, necessitating cleaning. I have found it possible largely to obviate these difficulties by preassembling the inner spring unit with its sisal padding in advance of shipment and in such a manner that the sisal fibers are largely covered and held in place and shedding of sisal is substantially eliminated, as is the upholsterer's time and labor heretofore needed to select and arrange the padding.

My invention therefore contemplates the provision of an inner spring unit preformed with padding which is so held to the unit that shedding of the padding material is substantially prevented and the other difficulties mentioned are overcome.

My invention further contemplates the provision of a spring cushion structure wherein the sisal fibers are arranged directly against the springs of the spring unit to sound-insulate the springs while the burlap backing for the sisal padding is arranged outwardly of the fibers thereby confining the sisal in place against shedding.

My invention further contemplates the use of padding in the form of a main inner layer, a fabric cover for the layer and a secondary outer layer, both layers being secured to the fabric cover, and the padding being adequately secured to the metallic inner spring unit to produce a prepacked spring unit capable of shipment to the place where the cushion is to be completed.

The various objects of the invention will be

clear from the description which follows and from the drawing, in which,

Fig. 1 is a perspective view of my new padded inner spring unit.

Fig. 2 is a front elevation, partly in section, of the completed cushion.

Fig. 3 is a perspective view of the two lengths of padding used to enclose the spring unit and forming the outer part of the preformed padded unit, showing the relative arrangement of the lengths.

In the practical embodiment of the invention which I have shown by way of example, the inner spring unit 10 is of the usual type comprising springs 11 and connecting wires 12 or the like suitably secured together. As the padding for the spring unit, I prefer to use two similar lengths of burlap-backed sisal padding. As shown in Fig. 3, the sisal layer 13 of the padding 10 is made up of heterogeneously arranged sisal fibers mounted on the inner face of the burlap backing sheet 14. The sisal fibers 13 are needled to project in the general form of loops through the outer face of the burlap sheet as at 15 and thereby to present a secondary set of sisal fibers on said outer face.

The fibers 15 are firmly secured to the burlap sheet and while comparatively few in number, said fibers form a secondary cushioning layer on the face of the burlap sheet, which layer is not likely to shed. The burlap sheet with its attached inner and outer sisal layers is cut to the desired length and arranged with the sisal layer 13 inwardly or in direct contact with the outer

35 most coils of the springs of the spring unit 10 whereby the sisal fibers tend to work their way to a slight extent into the inside of each of the springs 11 and between the adjacent coils of adjacent springs, thereby sound-insulating the 40 springs and silencing possible clicking noises which might occur when the coils move past each other when in contact.

Two lengths as 17 and 18 of burlap-backed sisal are used to provide an enclosing padding 45 for the spring unit. In each of the lengths, the secondary or outer layer extends along longitudinal parallel lines. In the length 17, the needling of the projecting fibers 15 is accomplished in the general direction of the lines 20, the 50 looped fibers 15, after needling, being brushed if desired to raise them an appreciable distance beyond the outer surface of the burlap sheet. The width of the upper surface of the length 17 is somewhat greater than the width of the spring structure 10 combined with the thicknesses of

the side flaps 21 and 22 of the padding length 18, whereby said upper surface 19 covers the spring structure and also covers and extends slightly past the side wall flaps 21, 22. From the surface 19 extend the end wall flaps 23, 24 which are of substantially greater height than the height of the spring structure to provide sufficient material at the extreme end part 40 of the length to be bent under the spring structure and to be engaged and held by the edge portion 25 of the padding length 18.

Similarly, the extreme end edge parts of the side flaps 21 and 22 of the length 18 are bent underneath the wide portion 19 of the padding length 17 to cover part of the upper surface of the spring unit and to provide peripheral portions as 26 and 36 thereon held in place by the respective projecting edge portions 27 and 30 of said wide part 19. The edge portion 21 of the length 17 is secured to the tucked in portion 26 at the edge of the flap 21 by suitable hog rings as 28 passing through both padding lengths and encompassing the border wire 12 of the spring structure, and if desired, passing also around the end coils of the marginal springs. Similar hog rings as 29 are provided at the other edge 30 of the piece 17, while at the bottom of the unit additional hog rings as 31 secure the tucked-in lower edge 40 of the flap 23 to the peripheral edge portion 25 of the length 18. The edge of the flap 24 is similarly tucked in and secured to the edge 32 of the length 18 and to the adjacent marginal wires of the cushion unit.

It will be noted that the tufts of sisal needed through the burlap backing for the length 18 are arranged along lines as 33 at substantially right angles to the similar lines 20 of the length 17, whereby it becomes immaterial which wide face of the unit is made the top or bottom, both being uniformly resilient. It will also be noted that the spring unit 10 is enclosed completely with sisal padding held thereto by the hog rings above-described, so that shedding of sisal to any material extent cannot occur. It will also be understood that the needed and brushed tufts of sisal along the lines 20 and 33 are in looped form and being connected through the burlap with the padding fibers 13, cannot shed, but serve as an auxiliary outer smaller cushioning layer on which the cotton batting 34 may be arranged. The auxiliary cushion thus formed by the projecting tufts enters the cotton batting 34 to some extent and holds said batting in place against its tendency to slip. The outer covering 35 of the cushion is secured in place in the usual manner outwardly of the cotton batting and serves to hold all the layers in place against displacement under the stresses of use.

It will be seen that the cushion as shown in Fig. 1 and consisting of the inner spring unit and the parts 17 and 18 assembled with and secured thereto, may be shipped as a unit to the place where the cushion is to be upholstered. There, the upholsterer need not arrange any sisal pads in place as has been heretofore necessary, but merely covers the cushion with the layer of cotton batting and applies and secures the outside cover to rapidly complete the cushion with a minimum of shedding of excess material, thereby keeping the material comparatively clean and neat.

While I have shown and described a specific embodiment of the invention, I do not wish to be understood as limiting myself thereto, but intend to claim the invention as broadly as may be permitted by the state of the prior art and the scope of the appended claims.

I claim:

1. A substantially square preassembled padded cushion unit adapted to be shipped and handled with a minimum loss of padding material comprising an inner spring unit, a first length of padding covering the top and two opposed end walls of the unit, a second length of padding covering the bottom and the other two opposed side walls of the unit, the first length having end edge portions bent into overlapping relation with the bottom wall of the second length, and the second length having end edge portions bent into overlapping relation to the top wall of the first length, each of the lengths comprising a sisal pad, a burlap backing having one face thereof in contact with the pad, and sisal fibers extending from the pad through the backing past the other face thereof and forming projecting tufts on said other face, the sisal pad being in contact with the spring unit and the projecting tufts being exposed on the outer face of the lengths, and hog rings each passing through adjacent edge portions of said lengths and around an adjacent part of the spring unit.

2. In a spring cushion, an inner spring unit, a pair of similar lengths of burlap-backed sisal padding, one of said lengths being arranged with the sisal thereof against the unit and covering one face and a pair of opposed walls of the unit, the other length being arranged with the sisal thereof covering the other face and the other pair of opposed walls of the unit, the sisal padding being needled through the burlap back of each length to form projecting tufts along longitudinal lines, the longitudinal lines of tufts of one length being at substantially right angles to the longitudinal lines of tufts of the other length, and means for securing the end parts of one length to the edge parts of the other length and to the spring unit to form a padded unit adapted to be shipped and handled with a minimum shedding of sisal from the padding.

3. A preassembled spring and padding unit for a spring cushion adapted to be shipped and handled without material loss of padding material comprising an inner spring unit having a top, bottom, two end walls and two side walls, and a pair of crossed and partly overlapping lengths of padding material, each length comprising a sisal layer arranged against the unit, a burlap backing for the sisal outwardly of the unit and sisal fibers projecting through the backing outwardly thereof, one of the lengths of padding covering the top and both end walls of the unit, the other length covering the bottom and both side walls of the unit, the respective end parts of the respective lengths being arranged in adjacent relation to the respective side parts of the other length, and securing means engaging adjacent end and edge parts of the respective lengths and passing around the adjacent part of the unit to secure said parts to each other and to the unit.
